UNITED STATES PATENT OFFICE.

HENRY MONTAGUE WALKER, OF MELBOURNE, VICTORIA, AUSTRALIA.

HAIR-WAVING DEVICE.

Application filed December 3, 1925, Serial No. 72,973, and in Australia January 13, 1925.

This invention consists of a device to be used to produce waves in the hair and is of a simple and inexpensive character and will not damage the most delicate hair.

5 Briefly stated the device consists of a pin of substantial width which is inserted under the hair, preferably damped, to be waved and to one end of said pin a spring wire clip is loosely attached thereto, said 10 clip having two spaced side wire members joined at the outer end which members when the spring clip is closed pass by the respective sides of the pin in close contiguity thereto and grip the hair against said pin 15 with the result that the hair being outwardly curved over the pin is formed with a wave if the device is left for a sufficient period in the hair. Unlike other devices whereby the hair is twisted on the pin or 20 concealed, the hair to be waved is exposed so that the person using the device may previously ascertain the resultant wave effect in the hair.

According to a practical and inexpensive 25 form of the device a wooden pin is employed and the spring clip consists of a length of wire bent at one end or doubled to form two parallel spaced side members with the ends of the wire joined and bent 30 to form a finger grip.

The other end of the clip is hinged to the back end of the pin and according to a simple means, that is inexpensive to manufacture and fit the parts, the pin is formed at 35 its front extremity with a point and near the back end with a shoulder and collar between which is a reduced neck. The rear bent end of the spring clip is bent upwardly to form an elbow and it is fitted to the 40 pin by springing the wire side members sufficiently apart to pass over the collar when they are released to engage the neck of the pin.

This practical form of the invention is 45 illustrated by the accompanying drawings whereof,

Figure 1 is a perspective view of the device in open position.

Figure 2 is a side elevation in closed position, and

Figure 3 a plan in the same position.

Figure 4 is an enlarged cross sectional view of the device showing the hair grip thereby.

55 Figure 5 is an elevation of another form of the device in open position.

The pin 1 may be straight as in Figures 1, 2 and 3 or slightly curved as in Figure 5, and preferably formed of a cylindrical piece of wood the diameter of which corresponds 60 to the breadth of the wave desired. In practice it is found that a pin of three eighths of an inch in diameter or with a breadth of three eighths of an inch is an average useful size. The pin is preferably 65 formed with a point 2 at its front end and with a reduced extremity 3 at its rear end said extremity being tapered or formed with a blunt point 4. Near the rear end of the pin an annular groove 5 is cut thus forming 70 a collar 6 joined by a neck 7 to a shoulder 8 the edge of which latter is rounded off as illustrated.

The wire forming the spring clip is bent as at 9 central of its length with the two 75 portions 10, 10 of the wire parallel to and separated a distance from each other and forming the side gripping members of the device. The side members are spaced apart a distance slightly less than the diameter 80 of the pin and its collar but spring apart on contact with the curved sides of the pin.

The free ends 11 of the pin are bent towards the side members 10, 10 to form an angle less than 90 degrees and are connected 85 by a cross piece to form a finger grip 12.

The bent rear end 9 of the clip is correspondingly bent towards the side members so as to form an angle less than 90 degrees therewith, the bends forming elbows 14. 90

When the clip is in the open position it will not become separated from the pin as the side members 10, 10 are held in the groove 5 by the collar 6 and shoulder 8, owing to the fact that the diameters of the 95 pin and collar are greater than the distance between the two side members.

To assemble the hair on the pin the clip is moved into the position shown in Fig. 1 and the collar 6 is grasped between the 100 thumb and one finger of the hand with the clip in the position shown so as to press the collar against the elbow 14 thus holding the clip in this position. The hair to be crimped preferably having been dampened 105 is then laid over the pin by means of the other hand; the point 2 and the finger grip 12 are grasped by the thumb and one finger respectively of the hand used in placing the hair over the pin. The spring clip is 110 pressed down by the finger imparting a lateral movement to the side members 10. As

- a result the latter are sprung apart first by contact with the rounded shoulder 8, which operates as a cam, and later by the hair on the pin until said members are about level with the underside of the pin or below the same as shown in Fig. 2. During this movement, the collar 6 acts as an abutment for the rear loop and prevents longitudinal movement of the clip relative to the pin.
- 10 The loop on the free end of the clip embraces the reduced end portion of the pin and as it slides transversely thereon, pressure on the finger grip 12 operates to tighten the grip of the clip on the pin.
- 15 By reason of the clip being held against forward movement through the rear loop bearing against the collar 6 inward pressure on the finger grip causes the side members 10 of the clip to curve as illustrated in
- 20 Figure 2, thus accommodating the device approximately to the curvature of the person's head. If, however, the pin is slightly curved lengthwise as in Figure 5, the side members of wire clip are correspondingly
- 25 curved.

It will be understood by the illustrations supplied that if a spring clip becomes broken or damaged, a new one may be readily substituted by simply springing the side members apart and passing the rear end of the pin between same till said members straddle the neck 7 and the bend 9 engages the extremity 3.

- I claim:
- 35 1. A hair waving device comprising a pin of a diameter corresponding to the width of wave desired and having reduced end portions, and a detachable spring clip having parallel sides spaced apart a distance 40 slightly less than the diameter of the pin, and terminating in laterally projecting loops converging towards their ends, said loops embracing said reduced portions and slideable thereon transversely of the pin, whereby the side members of the clip may 45 be moved laterally over the pin and assume their normal distance apart beyond the periphery of the latter.
2. A hair waving device comprising a pin of a diameter corresponding to the width of wave desired and having reduced end portions, and a detachable spring clip having parallel sides spaced apart a distance 50 slightly less than the diameter of the pin and terminating in laterally projecting loops converging towards their ends said loops embracing said reduced portions and slideable thereon transversely of the pin, whereby the sides of the clip may be moved laterally over the pin and assume their normal distance apart beyond the periphery of the latter, and means on the pin to prevent longitudinal movement of the clip relatively to the pin.
- 60 65 3. A hair waving device comprising a pin

of a diameter corresponding to the width of wave desired and having reduced end portions, and a detachable spring clip having parallel side members terminating in laterally projecting converging loops forming angles less than 90° with said sides, said loops embracing the reduced portions and movable thereon transversely to the pin.

4. A hair waving device comprising a pin of a diameter corresponding to the width of wave desired and having reduced end portions, one of said portions being tapered and the other having an abutment formed thereon, a spring clip having parallel side members spaced apart a distance slightly less than the diameter of the pin and terminating in converging loops forming angles less than 90° with said sides, one of said loops adapted to be moved on the tapered portion transversely thereto, said abutment engaging the other loop to prevent longitudinal movement of the clip thereby imparting a wedging action to the tapered portion.

5. A hair waving device comprising a pin of a diameter corresponding to the width of wave desired and having a tapered forward end portion and a reduced rear extremity having a collar formed thereon of substantially the same diameter of the pin, said collar spaced from the latter forming an annular groove between the pin and collar, a continuous wire spring clip having substantially parallel sides normally spaced apart a distance slightly less than the diameter of the pin, whereby it may be retained in said groove, said clip having a laterally extending converging loop at one end adapted to embrace said tapered end, and having a laterally extending converging loop at its other end for engagement with the rear side of the collar to maintain the front loop in friction engagement with said tapered portion.

6. A hair waving device comprising a round pin of a diameter corresponding to the width of wave desired and having both ends reduced, a collar between the body of the pin and one end of one of the reduced end portions, and a spring clip having parallel sides spaced apart substantially the diameter of the pin, the ends of said clip bent at an angle to the portion therebetween, one of the bent portions embracing one reduced end of the pin and the other bent portion embracing the other reduced end of the pin beyond the collar, said collar operating to retain the clip on the pin when the opposite end of the clip is disengaged from the pin and lying within the bend of the clip thereat.

7. A hair waving device comprising a pin of a diameter corresponding to the width of wave desired and having a tapered forward end portion and a reduced rear extremity, said extremity having a collar

formed thereon of substantially the same diameter of the pin and spaced from the latter forming an annular groove between the pin and collar, a continuous wire spring 5 clip having substantially parallel sides normally spaced apart a distance slightly less than the diameter of the pin and having a loop bent at an angle less than 90° at one end adapted to embrace said tapered end, which 10 operates as a wedge in said loop, said clip

having a corresponding loop at its other end for engagement with the rear side of the collar to maintain the front loop in locking engagement with said tapered portion said groove and collar cooperating to retain the 15 clip on the pin, said pin having a rounded shoulder to engage the side pieces in moving the latter onto the pin.

Dated this second day of November 1925.

HENRY MONTAGUE WALKER.
